UNITED STATES PATENT OFFICE.

HENRY P. CLAUSEN, OF MAMARONECK, NEW YORK, ASSIGNOR TO WESTERN ELECTRIC COMPANY, INCORPORATED, OF NEW YORK, N. Y., A CORPORATION OF NEW YORK.

ELECTRIC SWITCH.

Application filed November 9, 1923. Serial No. 673,645.

This invention relates to electric switches having a movable contact and a plurality of stationary contacts, the object being to provide a switch of this type in which the 5 movable contact may readily be locked in any one of its adjusted positions and readily unlocked for adjustment.

In accordance with the general features of the invention the movable contact arm is 10 so mounted for rotation or swinging movement with respect to the stationary contacts that pressure applied thereto in one direction will lock it against movement or rotation and pressure in the other direction will 15 release it for operation.

Specifically, the invention comprises a shaft supporting a contact arm which is adapted to engage with a plurality of contact points. The contact shaft is normally loose in its 20 bearing, permitting the arm to be moved over the contact points at will, but a slight pressure on the contact arm will cause it to be flexed downward against one of the contact points, binding the operating shaft in 25 its bearing and locking the switch arm in its operated position.

In accordance with another feature of the invention, means is provided for moving and holding the switch arm out of engagement 30 with the contact points when the switch is released from its bound position.

Other features and advantages of the invention and several possible applications thereof will be apparent from the following 35 description and the accompanying drawing, in which:

Fig. 1 is a fragmentary plan view of a rotary switch embodying the invention.

Fig. 2 is a partial sectional view taken on 40 the line 2—2 of Fig. 1, showing the switch in its normal position.

Fig. 3 is a view similar to Fig. 2, but showing the switch locked in its operated 45 position.

Fig. 4 is a partial sectional view taken on the line 4—4 of Figs. 5 and 6 showing a modified form of switch arm.

Figs. 5 and 6 are plan views showing two 50 different modifications of the invention.

Referring to the drawing, the device illustrated in Figs. 1, 2 and 3 consists of a plate 10 of insulating material upon which a plurality of projecting contacts 11 are mounted. A switch arm 12 is fastened to a shaft 13 55 which passes through a bushing or sleeve

14 of conducting material securely mounted in the plate 10. The opening in the sleeve 14 is large enough to permit a slight lateral movement of the shaft 13 whereby a tilting of the shaft will produce a locking effect between the shaft and the sleeve, as shown in Figs. 2 and 3. The shaft 13 is provided on the end adjacent the switch arm 12 with an operating knob 15 and at the other end with a pin 16 designed to limit the upward movement of the shaft in the sleeve 14. When the switch arm 12 is in the position shown in Fig. 2, it is held out of engagement with the contacts 11 by means of a leaf spring 17 which holds the shaft 13 in its extreme 60 upward position. A slight longitudinal pressure upon the knob 15, however, will cause the upper edge of the shaft 13 to press against the edge of the sleeve 14 and the lower edge of the shaft to contact with the 65 lower edge of the sleeve in such a manner that the shaft will be held very firmly in the position shown in Fig. 3, owing to the switch arm 12 flexing downward slightly 70 and binding against the contact 11. This 75 construction permits the establishment of a very satisfactory circuit connection between the shaft 13 and the sleeve or bushing 14, which elements are connected to the 80 circuits to be controlled. When the switch is in the position shown in Fig. 3, a slight pull 85 exerted on the knob 15 will loosen the shaft 13 in the sleeve 14 and the shaft and switch arm will be returned upward to the normal 90 position. When in this position, the switch may be rotated to any desired position 95 without any danger of momentarily connecting together adjacent contact points 11, and producing, for example, an arc where adjacent contacts are connected to circuits having considerable difference in potential.

In Figs. 4 and 5, contacts 11 and sleeve 14 are sunk below the surface of the plate 10 in holes 18. With this construction, a U-shaped switch arm 19, having a handgrip 20 of insulating material is employed having one end plugging into the sleeve 14 and the other engaging a contact 11. This construction is particularly useful where the 100 elements are connected to circuits having high voltages and where it is desirable to avoid accidental contact.

A somewhat similar modification is shown 105 in Fig. 6. In this construction, the sunken 110

contacts 11 are assembled in straight lines and are so arranged that a minimum space is required for mounting a comparatively large number of switch points. The switch 5 arm 20 employed in this construction is identical to that shown in Fig. 4, and may readily be removed from one sleeve 14 and plugged into another, in which position a slight pressure on the handgrip will produce a locking effect between the shaft and the sleeve. Other modifications and changes 10 in the specific details of construction herein shown and described may obviously be made without departing from the scope and spirit 15 of the invention.

What is claimed is:

1. A switching device comprising a bushing, a rotatable shaft loosely mounted in said bushing, and a switch arm carried by 20 said shaft and freely rotatable in one vertical position of said shaft, said switch arm being flexed when the shaft is depressed to lock the shaft against said bushing.
2. A switching device comprising a support, a sleeve mounted therein, a rotatable shaft loosely mounted in said sleeve and capable of vertical and lateral movement therein, and a switch arm carried by said shaft and freely rotatable in one vertical 25 and lateral position of said shaft and adapted to be locked in another vertical and lateral position thereof.
3. A switching device comprising a support, a sleeve mounted therein, a plurality 30 of contacts disposed about said sleeve, a rotatable shaft loosely mounted in said sleeve and capable of vertical and lateral movement therein, a switch arm carried by said shaft and adapted to engage with said contacts, said switch arm being so flexed that 35

it is out of engagement with said contacts when said shaft is raised and is bound against one of said contacts to lock the shaft against said sleeve when said shaft is lowered.

4. A switching device comprising a support, a sleeve mounted therein, a plurality of raised contacts mounted upon said support about said sleeve, a rotatable shaft loosely mounted in said sleeve and capable 50 of vertical and lateral movement therein, and a switch arm carried by said shaft and adapted to engage with such contacts, said switch arm being so flexed that it is held out of engagement with said contacts when said shaft is raised in said sleeve and is bound against one of said raised contacts to lock the shaft against said sleeve when the shaft is lowered therein.

5. A switching device comprising a support, a sleeve mounted therein, a plurality of raised contacts mounted on said support about said sleeve, a rotatable shaft loosely mounted in said sleeve and capable of vertical and lateral movement therein, a switch 60 arm carried by said shaft and adapted to engage with said contacts, said switch arm being so flexed that it is held out of engagement with said contacts when said shaft is raised in said sleeve and is bound against one of said contacts to lock the shaft against 65 said sleeve when said shaft is lowered therein, and a spring adapted to force and hold said shaft and switch arm upward when said shaft is released from its locked 70 position.

In witness whereof, I hereunto subscribe my name this 26th day of October A. D., 1923.

HENRY P. CLAUSEN.
